UNITED STATES PATENT OFFICE.

ANGUS R. GROSS, OF BALTIMORE, MARYLAND.

PARKING LIGHT.

Application filed September 26, 1921. Serial No. 503,353.

To all whom it may concern:

Be it known that I, ANGUS R. GROSS, a citizen of the United States, residing at Baltimore, in the county of Baltimore City 5 and State of Maryland, have invented certain new and useful Improvements in Parking Lights; and I hereby declare that the following is a full, clear, and exact description thereof, reference being had to the accompanying drawings, which form part of this specification.

This invention is a novel parking light for use on automobiles, but also adapted for use in other places and for other purposes. 15 The object of the invention is to provide a very simple electric lamp which can be cheaply constructed, and securely fastened upon the fender or other support.

Further objects of the invention are to 20 provide novel means for making the proper electric connections between the electric light bulb and an electric circuit when the light is inserted in the lamp.

I will explain the invention with reference to the accompanying drawing which illustrates a simple form of the lamp and the electrical connections of the bulb and refer to the claims for summaries of the novel features of the invention and the novel constructions and combinations of parts for 30 which protection is desired.

In said drawing:

Fig. 1 is a side view of the complete lamp as attached to the fender of a vehicle.

35 Fig. 2 is a longitudinal vertical section through the lamp casing detached.

Fig. 3 is a transverse vertical sectional view thereof on the line 3—3 Fig. 1.

Fig. 4 is an end view of the lamp casing.

40 Fig. 5 is a greatly enlarged sectional view through the lamp showing the electrical connections.

The lamp shown comprises a preferably short cylindric casing 1 open at both ends, but provided with an annular seat 1^a in each 45 end for a transparent jewel or glass 2, which is preferably confined therein by a split spring-ring 2^a seated in an annular recess 1^b in the end of the casing exterior to the jewel.

50 The casing is also provided with a hollow depending stem or T 1^c the lower end of the bore of the T being internally threaded for a short distance as at 1^d. In the body of the casing at the upper end of the bore of the T are formed short bayonet slots 1^e for the engagement of the usual side studs or

pins on the shank of the electric light bulb L which is of usual construction. This light is engaged with the bayonet slots by removing one or both of the jewels 2 (which may be 60 easily done by springing out the rings 2^a) and then inserting the lamp in place; then the casing is closed by replacing the jewels and rings. It will be seen that the lamp socket having the bayonet slots 1^e can be 65 and preferably is formed as an integral part of the lamp casing 1. Such casings can be drop forged.

Screwed into the lower end of the T 1^c of the casing is a tubular shank member 4 70 which has an internally projecting annular flange 4^a at its lower end and which is externally threaded and screwed directly into the casing T as far as the threads 1^d permit, thereby securely fastening the shank member 75 4 to the casing.

The lower part of the shank member is adapted to extend through an opening in the fender F or other support upon which the lamp is to be mounted (see Figs. 1 and 80 5), the lower end of the T 1^c rests upon the top of the fender, then it is secured thereto by a nut 5. In order to make a simple efficient electrical connection and circuit through the light L when placed in the casing, I employ the novel devices shown. Arranged axially within the shank member 4 is a metal member 6 having an axial recess 6^a in its upper end, and having its lower externally threaded and above the threaded 90 portion an exterior flange 6^b. Said flange is adapted to rest upon an annular washer W of suitable insulating material through which the threaded portion of the member 6 depends, and said washer is supported on the flange 4^a and centers the member 6 in the opening in the lower end of the member 4, and insulates it therefrom. Strung on the member 6 below the shank member 4 is a second washer W' of insulating material 95 which engages the under surface of the lower end of the member 4 or flange 4^a and is clamped thereagainst by a nut 6^c screwed onto the threaded portion of the member 6. By tightening nut 6^c the washers W W' are 100 clamped against the flanges 4^a which extend therebetween, thus securely centering and holding the member 6 into place, and the washers at the same time effectually insulate the latter from direct contact with the metal 105 of part 4, as indicated in Fig. 5.

Telescoping the upper end of member 6

is a hollow contact member 7, which is preferably slidably confined in the upper end of the member 6 so as to telescope therewith, and is normally projected outwardly by an 5 expansion helical spring 8 arranged within the bore 6^a and member 7. To prevent member 7 being disengaged from member 6, the lower end of the cap 7 may be slightly flanged outwardly as indicated at 7^a, and 10 the upper end of the part 6 slightly inturned as indicated at 6^b.

The contact member 7 normally projects upwardly in the shank 1^a so that when the lamp L is inserted in the casing and its 15 shank properly engaged with the slots 1^c the lower contact on the end of the lamp shank (as usual) will contact with the member 7 and thus close a metallic circuit for the electricity through the lamp. The current is 20 supplied through an electric conductor C which may be connected with any suitable source of electricity, and may be clamped between the nut 6^c and a nut 6^d screwed on the lower end of member 6 below the nut 6^c; 25 the return circuit being made through the metal of the lamp, and shank and supports in the usual well known manner.

It will be seen that the invention provides a very simple inexpensive lamp; that a very 30 small bulb may be used therein; and that the means for making the electric circuit through the light are very simple and can be readily assembled in and connected with the shank member before it is connected with 35 the casing.

Claims:

1. In a parking lamp a casing having a body open and a hollow T integral with the body having an electric light socket with 40 bayonet slots in its inner end, with a threaded shank member threaded into the lower end of the T and projecting therefrom, and a fastening nut secured on the lower end of the shank member.

45 2. In a parking light as set forth in claim 1 the shank member being tubular, and an electrical contact device carried by said shank member.

3. In a parking lamp a casing having a 50 body open at both ends and a T having an electric light socket provided with bayonet slots in its inner end, all formed integral; jewel lights in each end of the body detachably attached thereto and means for fastening the lights in place, with a threaded shank member threaded into the lower end of the T and projecting therefrom and fastening nut secured on the lower end of the shank member.

60 4. In a parking light as set forth in claim 3 the shank member being tubular and an electrical contact device carried by said shank member.

65 5. In a parking light the combination of a casing, a shank member engaging the cas-

ing and having an inwardly projecting flange at its lower end, a threaded member passing through the opening in the shank, washers above and below the bottom of the shank member to position the said threaded member in the shank member and insulate it therefrom, a nut for fastening the washers in place, and a contact member telescopically engaged with the upper end of said threaded member.

70 6. In a parking light as set forth in claim 1 the shank member having an inwardly projecting flange at its lower end, a threaded member passing through the opening in the shank, washers above and below the bottom of the shank member to position the said member in the shank member and insulate it therefrom, a nut for fastening the washers in place, and a contact member telescopically engaged with the upper end of said threaded member.

75 7. In a parking light as set forth in claim 3, the shank member having an inwardly projecting flange at its lower end, a threaded member passing through the opening in the shank, washers above and below the bottom of the shank member to position the said member in the shank member and insulate it therefrom, a nut for fastening the washers in place, and a contact member telescopically engaged with the upper end of said threaded member.

80 8. In a parking light as set forth in claim 1, the shank member having an inwardly projecting flange at its lower end, a threaded member passing through the opening in the shank, washers above and below the bottom of the shank member to position the said threaded member in the shank member and insulate it therefrom, said threaded member having a hollow upper end, a hollow contact member telescopically engaging the upper end of the threaded member, and a spring 85 confined in the contact member and threaded member for normally raising the contact member.

90 9. In a parking light as set forth in claim 1, the shank member having an inwardly projecting flange at its lower end, a threaded member passing through the opening in the shank, washers above and below the bottom of the shank member to position the said member in the shank member and insulate it therefrom, a nut for fastening the washers 95 in place; a contact member telescopically engaged with the upper end of said threaded member, said threaded member having a hollow upper end, a hollow contact member telescopically engaging the upper end of the threaded member and a spring confined in 100 the contact member and threaded member for normally raising the contact member.

105 10. In a parking light as set forth in claim 1, the shank member having an inwardly projecting flange at its lower end, a threaded member passing through the opening in the shank, washers above and below the bottom of the shank member to position the said member in the shank member and insulate it therefrom, a nut for fastening the washers in place; a contact member telescopically engaged with the upper end of said threaded member, said threaded member having a hollow upper end, a hollow contact member telescopically engaging the upper end of the threaded member and a spring confined in 115 the contact member and threaded member for normally raising the contact member.

120 11. In a parking light as set forth in claim 3, the shank member having an inwardly projecting flange at its lower end, a threaded 125 member passing through the opening in the shank, washers above and below the bottom of the shank member to position the said member in the shank member and insulate it therefrom, a nut for fastening the washers in place; a contact member telescopically engaged with the upper end of said threaded member, said threaded member having a hollow upper end, a hollow contact member telescopically engaging the upper end of the threaded member and a spring confined in the contact member and threaded member for normally raising the contact member.

- member passing through the opening in the shank, washers above and below the bottom of the shank member to position the said member in the shank member and insulate it therefrom, a nut for fastening the washers in place; a contact member telescopically engaged with the upper end of said threaded member, said threaded member having a hollow upper end, a hollow contact member 5 telescopically engaging the upper end of the threaded member, and a spring confined in the contact member and threaded member for normally raising the contact member.
11. In a parking lamp a one piece casing 15 comprising a body open at both ends, and a T; said body having an electric light socket at the inner end of the T and bayonet slots in the body at the sides of the socket.
12. In a parking lamp a one piece casing 20 comprising a body open at both ends, and a T; said body having an electric light socket at the inner end of the T and bayonet slots in the body at the sides of the socket; and a light in each end of the body.
- 25 13. In a parking lamp a one piece casing comprising a body open at both ends, and a T; said body having an electric light socket at the inner end of the T and bayonet slots in the body at the sides of the socket; 30 a jewel light in each end of the body detachably attached thereto and projecting beyond the ends of the body, and means for fastening the lights in place.
14. In combination with a parking lamp casing as set forth in claim 12, a shank 35 member threaded into the lower end of the T and projecting therefrom, and a fastening nut on the lower end of the shank member.
15. In combination with a parking lamp casing as set forth in claim 12, a shank 40 member threaded into the lower end of the T and projecting therefrom, and a fastening nut on the lower end of the shank member, the shank member being tubular, and an electrical contact device carried by said 45 shank member.
16. A parking lamp, including a tubular socket element having an inwardly projecting flange at one end, an insulation member on each side of said flange, a contact member within the tubular socket, means to attach said socket to an automobile fender including a nut threaded to said socket and adapted to support the lamp on an automobile fender and a light casing secured to the 50 55 socket.

In testimony that I claim the foregoing as my own, I affix my signature.

ANGUS R. GROSS.
